The ornamental design for a dermatological system, as shown and described.

DESCRIPTION

FIG. 1 illustrates a top side perspective view of a dermatological system employing an ornamental design in accordance with the present invention;

FIG. 2 illustrates a left side view of the dermatological system of FIG. 1;

FIG. 3 illustrates a right side view of the dermatological system of FIG. 1;

FIG. 4 illustrates a front side view of the dermatological system of FIG. 1;

FIG. 5 illustrates a back side view of the dermatological system of FIG. 1;

FIG. 6 illustrates a top view of the dermatological system of FIG. 1; and,

FIG. 7 illustrates a bottom view of the dermatological system of FIG. 1.

All features illustrated in phantom line are expressly disclaimed and form no part of the claimed design.
